UNITED STATES PATENT OFFICE.

CHARLES F. SPERY, OF CHICAGO, ILLINOIS.

CLAMP.

1,330,355.

Specification of Letters Patent. Patented Feb. 10, 1920.

Application filed April 23, 1917. Serial No. 164,016.

To all whom it may concern:

Be it known that I, CHARLES F. SPERY, a citizen of the United States, residing at Chicago, in the county of Cook and State 5 of Illinois, have invented certain new and useful Improvements in Clamps, of which the following is a specification.

This invention relates more particularly to clamps which are used for attaching or 10 securing one device to another such, for instance, as attaching a telephone to a support or bracket, or attaching a cylindrical member to a stand or support.

In forms of clamps heretofore used for 15 attaching telephones to brackets, screws are commonly used for tightening the jaws of the clamps. It is somewhat troublesome and more or less difficult to hold the several parts while the screws are being inserted 20 and the clamp properly adjusted. The objects of the present invention are to provide a clamp of the character indicated which will have no screws or bolts for tightening the same; to provide a clamp 25 which may be readily applied to a telephone or the like, and the parts quickly attached without the necessity of using any tools; to provide an improved form of clamp of the character described which will be 30 simple in construction and will be particularly neat and attractive in appearance; and in general, to provide such advantages as will appear more fully from the following description.

35 In the accompanying drawings illustrating this invention:

Figure 1 is a side view of the clamp shown 40 in connection with a telephone and bracket.

Fig. 2 is a plan view.

Fig. 3 is a front view; and,

Fig. 4 is a sectional view taken on the lines 45—4 of Figs. 1 and 2.

For convenience in description this invention may be considered as applied to a telephone bracket, although it may, of course, be used for other purposes. As shown in the drawings, the bracket 5 has a rod or shaft 6 which is engaged by the clamp. The clamp comprises, in general, two portions, 50 one of which is fixed to the rod, while the other portion engages with the tubular part 7 of the telephone. The portion which is applied to the rod or shaft 6 is preferably made of a single piece of metal which is 55 bent to form a cylindrical part 8 which sur-

rounds the rod, and has two projecting flat parts 9 which extend out from the tubular part 8, and are fastened together in any suitable manner. This may be conveniently done by forming tongues 10 at the ends of one of these parts and bending these tongues in over the adjacent opposed part. The outer portions of the metal plate are bent, as shown in Figs. 1, 2, and 4, to form converging channels 11 which coact to provide a 60 tapered socket for the portion 12 of the clamp which embraces the tube 7. This portion may, in some instances, be made of a single piece, but is preferably made in two pieces when it is to be used for attaching a telephone. One of these pieces is provided with a tongue 13 which engages with a suitably shaped slot or recess 14 in the opposite piece, so as to make a smooth and inconspicuous joint. The edges 15 of the two 70 parts are bent, as shown in Figs. 1, 2, and 4, to form converging, engaging members for engagement with the grooves 11.

The operation and advantages of this device will be readily apparent to those skilled 80 in the art. The bracket 5 is preferably made with the coacting part of the clamp attached thereto, so that the only loose portions are the two parts which engage with the telephone tube 7. When the telephone 85 is to be attached to the bracket, the operator merely places the sleeve 12 in position, which may be readily done on account of the jointed connection, then slips the tapered tongue 15 into the corresponding tapered 90 socket 11, and then presses down on the part 12 until the parts are tightened. It will be seen that this makes an exceedingly simple device to apply and, while it will hold the parts securely in position, it may also be 95 readily disassembled when desired.

It will be observed that various changes may be made in the form of construction for applying the device in different ways, without departing from this invention and, therefore, I do not wish to limit myself to the exact construction shown and described except as set forth in the following claims in which I claim:

1. The combination of a single plate of 105 metal bent to form a cylinder at one side and a socket at the other side, and a coacting clamping member comprising two jointed sections forming a cylinder with tapered tongues for engagement with said socket, 110

the arrangement being such that the second named member will be tightened around the part to be held when the tongues are pressed into the socket.

5. 2. The combination with a telephone bracket having a vertical rod, of a clamping member rotatably engaging with said rod

and having a tapered socket, a second clamping member adapted to encircle the tube of the telephone, said member comprising two portions, the adjacent edges of which are bent to form tapered tongues for engagement with said socket.

CHARLES F. SPERY.
